[57] CLAIM

The ornamental design for a vehicle aerodynamic fairing, as shown and described.

DESCRIPTION

FIG. 1 is a downward looking perspective view taken from the front and right side of the vehicle aerodynamic fairing embodying our new design;

FIG. 2 is a top plan view thereof;

FIG. 3 is a side elevational view taken from the left-hand side thereof; and

FIG. 4 is a front elevational view thereof.

The portions shown in broken lines on the drawings show a portion of the vehicle cab on which the vehicle aerodynamic fairing might be mounted and are included for illustrative purposes only and forms no part of the claimed design.
